[57] CLAIM

The ornamental design for a portable desk for use atop an open trash receptacle, as shown and described.

DESCRIPTION

FIG. 1 is a perspective view of a portable desk for use atop an open trash receptacle, showing my new design; FIG. 2 is a left side elevational view thereof; FIG. 3 is a top plan view thereof; FIG. 4 is a front elevational view thereof; FIG. 5 is a rear elevational view thereof; and, FIG. 6 is a bottom plan thereof.

The broken lines shown in FIGS. 1, 2 and 4 indicate environmental structure and form no part of the claimed design.

FIG. 1

FIG. 2

FIG. 3

FIG. 4

FIG. 5

FIG. 6
